UNITED STATES PATENT OFFICE.

FRED B. CRITTENDEN, OF NEW YORK, N. Y.

DESIGN FOR A CORN-CUTTING SCOOP.

SPECIFICATION forming part of Design No. 33,327, dated October 9, 1900.

Application filed September 14, 1900. Serial No. 30,076. Term of patent 14 years.

To all whom it may concern:

Be it known that I, FRED B. CRITTENDEN, a citizen of the United States, and a resident of the city of New York, borough of Brooklyn, in the county of Kings and State of New York, have invented and produced a new and original Design for a Corn-Cutting Scoop, of which the following is a full, clear, and exact description.

Reference is to be had to the accompanying drawings, forming a part of this specification, in which similar characters of reference indicate corresponding parts in both the views.

Figure 1 is a plan view of a corn-cutting scoop, showing my design; and Fig. 2 is a longitudinal sectional elevation of the same on the line 2 2 in Fig. 1.

The leading feature of the design consists in the configuration of the corn-cutting scoop made the subject of the accompanying illustration.

The design in its entirety consists of a handle A terminating in a scoop B, the bottom of which appears at its front end with longitudinally-extending triangular teeth C, the sides of which are beveled, the end teeth C' forming the forward portions of the sides of the scoop, as is plainly indicated in the drawings.

Having thus fully described my invention, I claim as new and desire to secure by Letters Patent—

The design for the corn-cutting scoop herein shown and described.

In testimony whereof I have signed my name to this specification in the presence of two subscribing witnesses.

FRED B. CRITTENDEN.
